UNITED STATES PATENT OFFICE.

WARD E. WRIGHT, OF CHICAGO, ILLINOIS, ASSIGNOR TO UNION SPECIAL MACHINE COMPANY, OF CHICAGO, ILLINOIS, A CORPORATION OF ILLINOIS.

SEWING-MACHINE.

1,145,647.

Specification of Letters Patent.

Patented July 6, 1915.

Application filed February 13, 1909. Serial No. 477,759.

To all whom it may concern:

Be it known that I, WARD E. WRIGHT, a citizen of the United States, residing at Chicago, in the county of Cook, State of Illinois, have invented certain new and useful Improvements in Sewing-Machines, of which the following is a description, reference being had to the accompanying drawing and to the letters and figures of reference marked thereon.

The invention relates to new and useful improvements in sewing machines, and more especially to the feeding mechanism of a sewing machine.

The invention as herein shown is especially adapted to machines of the character which operate to full or gather a piece of fabric prior to stitching the same, or full or gather one piece of fabric relative to another, and secure the same together.

When placing a binding strip or the like upon a knitted fabric, and more especially when binding across the wales of the knitted fabric, the knitted fabric is very apt to become stretched or distorted in the stitching operation. By my improved mechanism, the knitted fabric may be fed slightly faster than the binding strip or non-elastic fabric, thus overcoming the tendency of the knitted fabric to stretch, so that the two pieces of fabric will be evenly and smoothly stitched together. It is sometimes desirable, when stitching one piece of fabric to another of the above character, to cause the fulling action of the feeding mechanism to cease, as for example, when crossing stay strips or the like.

The invention, therefore, contemplates providing mechanism whereby the fulling action of the feeding mechanism may be rendered ineffective whenever desired, without stopping the stitching mechanism.

The invention consists in the parts, arrangements and improvements hereinafter shown, described and pointed out in the appended claims.

In the drawings, which show by way of illustration, one embodiment of the invention, Figure 1 is an end elevation with the work support removed, and certain parts in section, showing a machine with my invention applied thereto; Fig. 2 is a view from the front of the machine; Fig. 3 is a view from the rear of the machine; Fig. 4 is a detail view, showing the auxiliary feed dog

operating mechanism; Fig. 5 is a detail, partly in section, of the hinged connection in the feed bar for the auxiliary feed dog; Fig. 6 is a top plan view of the auxiliary feed dog operating mechanism; Fig. 7 is a top plan view, showing the relation of the auxiliary feed dog to the fabric, when the machine is adapted for stitching a binding on to a fabric; and Fig. 8 is a detail view in plan, showing the relation of the feed dogs.

The overhanging arm 1 carries a needle bar 2, at its forward end, which is reciprocated by the usual needle lever 3. The needle bar 2 carries a needle 4, which is of the ordinary construction. Coöperating with the needle 4 is a looper 5, which is pivoted at 6 to a looper rocker 7, which is also of the usual construction. The looper 5 is oscillated by means of the link 8. The presser bar 9 is mounted in the forward end of the machine, and carries a presser foot 10. The presser bar is provided with the usual stud 11, which is engaged by a lever 12, connected to a suitable treadle or knee shift, whereby the presser bar may be lifted whenever desired. The presser bar is guided in its movements by the usual guide bar 13, which moves up and down with the presser bar. The main feed dog 14 is carried by the feed bar 15, which is pivoted at 16 to a rocking frame or feed rocker 17, pivoted in turn at 18 to the bed plate 19 of the machine. The frame 17 is rocked back and forth by means of the usual arm 20, which is connected by means of a link 21 with a stud 22, adjustably mounted in a disk 23, carried by the main shaft 24. The feed bar is raised and lowered by means of the usual eccentric 25, mounted on the main shaft 24, and engaging the yoke 26 carried by the main feed bar 15. These parts are of the usual construction, and will not need further description.

The auxiliary feed dog 27 is rigidly secured to a rocking lever 28 by means of a screw 29. Said lever 28 is slabbed at its lower end to form a bearing seat for the feed dog. This auxiliary feed dog is located above the work support, and is so positioned as to engage the fabric at one side of the stitching point and in advance of the main feed dog 14. This position of the parts is especially adapted for stitching one piece of fabric to another. If, however, it was desired to full in a single piece of fabric, the auxiliary feed

dog might be positioned directly in front of the stitching mechanism, and extend entirely across the front of the main feed dog.

The lever 28, supporting the auxiliary feed dog 27, is pivoted between the forked ends 30 and 31, of a bracket arm 32, which is carried by the auxiliary feed bar 33. The bracket arm 32 extends upwardly, as at 34, from its connection with the auxiliary feed dog 33, and then laterally, as at 35, so that the auxiliary feed dog may be supported and operated at the opposite side of the stitching point from the auxiliary feed bar 33.

15 The auxiliary feed bar 33 is made in two parts 36, 37, which are connected by means of a pivot pin 38. The part 37 consists of an extended sleeve 39, which surrounds the pivot pin 16 between the rocking frame and the main feed bar 15. The sleeve 39 has a forwardly extending arm 40, which is provided with a shoulder 41, which in turn engages a shoulder 42 on the forward part 36 of the auxiliary feed bar. When the shoulders 41 and 42 are brought into contact, the movement of the portion 37 of the auxiliary feed bar relative to the portion 36, is limited. The sleeve 39 is also provided with a rearwardly extending arm 43, which is 20 connected by means of a link 44 with one arm 45 of a rock lever which is mounted on a pivot bolt 18 for the rocking frame 17. The other arm 46 of the rock lever may be connected by any suitable means with a foot 25 treadle or with a knee shift.

The forward portion of the auxiliary feed bar 33 rests upon an eccentric 47, mounted on the main shaft 24. The bracket arm 48 carried by the auxiliary feed bar engages 30 the under side of the eccentric 47, so that as the eccentric 47 rotates, the auxiliary feed bar will be moved up and down positively. A spring 49 is secured by suitable screws 50 to the back side of the rocking frame 17. Said spring extends up over the rocking frame, and has its forward end bent upon itself, so as to rest upon the forward portion 36 of the auxiliary feed bar. Said spring tends normally to rotate the part 37 55 of the auxiliary feed bar about its pivotal support, and also the part 36 of the auxiliary feed bar about the eccentric 47, so that the shoulders 41 and 42 are held in contact with each other.

55 During the feeding movements of the auxiliary feed dog, the parts of the auxiliary feed bar move back and forth, as though they were formed of a single part. The lever 28 which carries the auxiliary feed bar 27, is provided at its upper end with a segmental slot 51. A link 52 is connected at one end to a ball stud 53, projecting from a collar 54, carried by the guiding bar 13 of the presser foot mechanism. The other end 60 of the link 52 is connected to a ball stud 55, which is adjustably secured in the slot 51. The bracket arm 32 is provided with a slot 56, which engages a set screw 57, carried by the auxiliary feed bar. It will, therefore, be seen that the bracket arm may be adjusted vertically, and by this adjustment the working position of the auxiliary feed dog relative to the work support, be varied. As herein shown, the machine is provided with a folder or a binding guide 57, which may 70 be of any desired character. The binding B as it is led from the binder, passes to the stitching mechanism at one side of the auxiliary feed dog, while the main fabric F is guided between the folded portions of the 75 binding, and is engaged by the auxiliary feed dog.

When it is desired to place a binding strip upon an elastic fabric, the auxiliary feed dog will operate upon the elastic fabric, and feed the same slightly faster than the binding strip, so that all tendency of the elastic fabric to stretch is overcome, and the elastic fabric is evenly and smoothly stitched to the binding strip. If a stay strip or other non-elastic portion of the fabric is brought to the stitching mechanism, the operator may readily, if desired, throw the auxiliary feed dog out of contact with the material until the stay strip has passed through the stitching mechanism.

The operation of the auxiliary feed dog is as follows: When the rocking frame 17 is oscillated back and forth, the bracket arm 32 is also moved back and forth. The lever 28 carrying the auxiliary feed dog will, therefore, be vibrated about its pivotal connection with the link 52. This gives to the auxiliary feed dog its feeding movement. As the eccentric 47 rotates, the auxiliary feed dog will be raised and lowered, which will also raise and lower the bracket arm 34, and this in turn will raise and lower the lever 28, carrying the auxiliary feed dog. The link 52 in this movement of the auxiliary feed dog swings about the ball stud 53 as a center. The movement of the auxiliary feed bar and the bracket arm carried thereby back and forth with the rocking frame 17, is, of course, in unison with the movements of the main feed dog. The swinging of the lever 28, however, about the pivotal point 55 will multiply the movement of the auxiliary feed bar, so that the auxiliary feed dog will move a greater distance than the main feed dog. This gives to the auxiliary feed dog a differential movement relative to the main feed dog. The amount of the differential movement may be varied by adjusting the ball stud 55, in the segmental slot 51, of the lever 28. When the ball stud 55 is moved away from the pivotal connection between the bracket 32 and the lever 28, the movements of the auxiliary feed dog will be decreased, and when said pivotal point is moved 110 115 120 125 130

in the opposite direction, the movements of the auxiliary feed dog relative to the main feed dog will be increased. When it is desired to render the feeding movements of the auxiliary feed dog ineffective, the rocking lever at the rear of the machine is depressed. This movement of the rocking lever through the link 44, will swing the rear portion of the auxiliary feed bar about its pivot, which will raise the pivotal connection between the portions of the auxiliary feed bar, which in turn will swing the forward portion 36 of the auxiliary feed bar about the eccentric 47 as an axis, thus throwing forward the bracket arm 32. This forward movement of the bracket arm 32 will carry forward the lever 28, swinging the same about its pivotal point 55, and thus raise the auxiliary feed dog 27 from engagement with the fabric. The movements of the auxiliary feed dog will continue as before, but inasmuch as the feed dog is moved from contact with the fabric, it will be rendered ineffective. Inasmuch as the link 52 is pivoted to the guiding bar of the presser foot mechanism, whenever the presser foot is raised for the insertion of material, the stud 53 to which the link 52 is pivoted, will be raised, and this will throw backward the upper end of the lever 28, thus raising the auxiliary feed dog, so that the work may be readily inserted.

Having thus described my invention, what I claim as new and desire to secure by Letters Patent, is:—

1. The combination of a work support, stitch forming mechanism, feeding mechanism including a main feeding member, means for moving said main feeding member to feed the fabric, an auxiliary feeding member, means for raising and lowering said auxiliary feeding member, and for moving said auxiliary feeding member back and forth to feed the material, means whereby said auxiliary feeding member may be given a differential movement relative to the main feeding member, and means whereby the auxiliary feeding member may be moved while in motion, out of operative engagement with the fabric, without stopping the feed of the material by the main feeding member and without stopping the stitch forming mechanism.

2. The combination of a work support, stitch-forming mechanism, feeding mechanism including a main feeding member, a fulling member engaging the upper surface of the fabric, and means whereby the fulling member may be moved while in motion out of operative engagement with the fabric, without stopping the feeding action of the main feeding mechanism, and without stopping the stitch forming mechanism.

3. The combination of a work support, stitch forming mechanism, feeding mecha-

nism including a main feeding member, an auxiliary feeding member, means for moving said auxiliary feeding member into and out of engagement with the fabric, means for moving the auxiliary feeding member back and forth to feed the fabric, means for giving the auxiliary feeding member a differential movement relative to the main feeding member, and means for moving the auxiliary feeding member out of operative engagement with the work, while said member is in motion to render its feeding action ineffective, without stopping the feeding action of the main feeding member, and without stopping the stitch forming mechanism.

4. The combination of a work support, stitch forming mechanism, feeding mechanism including a main feed dog and an auxiliary feed dog located above the work support and engaging the fabric in front of the stitching point, means for giving the auxiliary feed dog a differential movement relative to the main feed dog, means whereby the auxiliary feed dog may be moved out of engagement with the fabric while in motion, and without stopping the feeding action of the main feed dog, and without stopping the stitch forming mechanism.

5. The combination of a work support, stitch-forming mechanism, feeding mechanism including a main feed dog, an auxiliary feed dog located above the work support, means for giving said auxiliary feed dog a differential movement relative to the main feed dog, means for changing the position of the auxiliary feed dog for varying thicknesses of material, and means for rendering the differential movement of the auxiliary feed dog ineffective without stopping the feeding action of the main feed dog and without stopping the stitching mechanism.

6. The combination of a work support, stitch-forming mechanism, feeding mechanism including a main feed dog, for engaging the material in rear of the stitching point, an auxiliary feed dog located above the work support and engaging the material at one side of and in front of the stitching point, means for giving said auxiliary feed dog an up and down and back and forth movement, means for giving said auxiliary feed dog a differential movement relative to the main feed dog, means whereby the differential movement may be varied, and means whereby the auxiliary feed dog may be moved while in motion out of operative engagement with the fabric, without stopping the feeding action of the main feed dog and without stopping the stitch-forming mechanism.

7. The combination of a work support, stitch-forming mechanism, feeding mechanism including a main feed dog, an auxiliary feed dog, means for moving said auxiliary

feed dog back and forth to feed the fabric, means for giving said auxiliary feed dog a differential movement relative to the main feed dog, means for varying said differential movement, and independent means whereby said differential movement may be rendered ineffective.

8. The combination of a work support, stitch-forming mechanism, feeding mechanism including a main feed dog, an auxiliary feed dog located above the work support and engaging the fabric in advance of the stitching point, means for giving said auxiliary feed dog a differential movement relative to the main feed dog, means whereby said differential movement may be varied, and independent means whereby said auxiliary feed dog may be moved out of operative engagement with the fabric, without stopping the stitch-forming mechanism and without stopping the action of the main feed dog.

9. The combination with a work support, of stitch-forming mechanism, feeding mechanism including a main feed dog, an auxiliary feed dog, a bar to which said auxiliary feed dog is pivoted, means for moving said bar back and forth in unison with the main feed dog, means for swinging said auxiliary feed dog on its pivot whereby it is given a differential movement relative to the main feed dog, means for varying said differential movement, and independent means for rendering said differential movement ineffective without stopping the stitch-forming mechanism.

10. The combination of a work support, stitch-forming mechanism, feeding mechanism including a main feed dog, an auxiliary feed dog located above the work support and engaging the fabric at one side of and in advance of the stitching point, a feed bar to which said auxiliary feed dog is pivoted, means for moving said feed bar back and forth in unison with said main feed dog, means for swinging said auxiliary feed dog about its pivotal support, whereby the same is given a differential movement relative to the main feed dog, means for varying said differential movement, and means for moving said auxiliary feed dog out of operative engagement with the fabric, without stopping the stitch-forming mechanism.

11. The combination with a work support, of a feeding mechanism including a feed dog, a feed bar to which said feed dog is pivotally connected, means for moving said feed bar back and forth and up and down for giving the feeding movements to said feed dog, a link pivotally connected to said feed dog and to a relatively stationary part of the machine.

12. The combination with a work support, of a feeding mechanism including a feed dog, a feed bar to which said feed dog is pivotally connected, means for moving said

feed bar back and forth and up and down for giving the feeding movements to said feed dog, a link pivotally connected to said feed dog and to a relatively stationary part of the machine, and means for adjusting the connection of said link to said auxiliary feed dog.

13. The combination with a work support, of a feed dog, a feed bar, a bracket arm carried by said feed bar to which said feed dog is pivotally connected, a link pivotally connected to said feed dog and to a relatively stationary part of the machine, an eccentric for moving said feed bar up and down, means for moving said feed bar back and forth, means for turning the forward end of said feed bar about said eccentric, whereby the working position of the feed dog relative to the work support may be varied.

14. A feeding mechanism including in combination, a feed bar, a rocking frame to which said feed bar is pivoted, means for rocking said frame, an eccentric for raising and lowering said feed bar, said feed bar being made in sections hinged together, a feed dog pivotally connected to said feed bar, a link pivoted to said feed dog and to a relatively stationary part of the machine, and means for swinging said sections of the feed bar relative to each other, so as to change the working position of the feed dog relative to the work support.

15. A feeding mechanism including in combination, a work support a feed bar, a rocking frame to which said feed bar is pivoted, means for rocking said frame, an eccentric for raising and lowering said feed bar, said feed bar being made in sections hinged together, a feed dog pivotally connected to said feed bar, a link pivoted to said feed dog and to a relatively stationary part of the machine, a rock lever pivoted on a relatively stationary part of the machine, a link connecting said rock lever to one section of the feed bar, whereby the sections of the feed bar may be moved relative to each other, so as to vary the working position of the feed dog relative to the work support.

16. A feeding mechanism including in combination, a feed bar, an eccentric for supporting the forward end of said feed bar, a feed dog carried by said feed bar, said feed bar being made in sections pivotally connected together, a rocking frame to which the rear section of the feed bar is pivoted, a rock shaft, a link connecting said rock shaft to the rear section of the feed bar, whereby said sections may be moved relative to each other.

17. A feeding mechanism including in combination, a feed bar, an eccentric for supporting the forward end of said feed bar, a feed dog carried by said feed bar, said feed bar being made in sections pivot-

ally connected together, a rocking frame to which the rear section of the feed bar is pivoted, a rock shaft, a link connecting said rock shaft to the rear section of the feed bar, whereby said sections may be moved relative to each other, a stop for limiting the movement of said sections of the feed bar in one direction, and a spring connected to said rocking frame and bearing upon said feed bar.

18. The combination with a work support, a main feeding mechanism including a main feed bar, a rocking frame to which said main feed bar is pivoted, means for moving said feed bar up and down, an auxiliary feed bar pivoted to said rocking frame, means for moving said auxiliary feed bar up and down, a bracket arm carried by said auxiliary feed bar and extending above the work support, a lever pivoted to said bracket arm, an auxiliary feed dog carried by said lever, a link pivoted at one end to said lever and at its other end to a relatively stationary part of the machine, and means for swinging said auxiliary feed bar about its lifting means as an axis, whereby the working position of the auxiliary feed dog relative to the work support may be varied.
19. The combination with a work support, a main feeding mechanism including a main feed bar, a rocking frame to which said main feed bar is pivoted, means for moving said feed bar up and down, an auxiliary feed bar pivoted to said rocking frame, means for moving said auxiliary feed bar up and down, a bracket arm carried by said auxiliary feed bar and extending above the work support, a lever pivoted to said bracket arm, an auxiliary feed dog carried by said lever, a link pivoted at one end to said lever and at its other end to a relatively stationary part of the machine,

said auxiliary feed bar being made in sections pivotally connected together, a rocking shaft pivoted to a stationary part of the machine, a link connecting said rock shaft with one of the sections of said auxiliary feed bar, whereby said sections of the auxiliary feed bar may be swung about their pivotal connections and the auxiliary feed dog lifted from the fabric.

20. The combination of a work support, a presser foot, a presser bar carrying the same, stitch-forming mechanism, feeding mechanism including a main feed dog, an auxiliary feed dog, a differential means for giving said auxiliary feed dog feeding movement relative to the main feed dog including a link pivotally connecting the said auxiliary feed dog and to the presser bar.

21. In a sewing machine, a feeding mechanism including a main feeding member, an auxiliary feeding member, common means for giving said feeding members their back and forth movements, an eccentric for giving said auxiliary feeding member its up and down movements, and means for swinging said feed member bodily on said eccentric.

22. In a sewing machine, a feeding device, a feed rocker, a lever pivoted to and moving with said feed rocker, a feed dog, a feed dog supporting member pivoted to said lever and partaking of the movements of the rocker, an eccentric to give said member its vertical movements and also acting as a pivotal point for said feed dog supporting member.

In testimony whereof I affix my signature, in presence of two witnesses.

WARD E. WRIGHT.
